UNITED STATES PATENT OFFICE.

IRVEN R. MARGETTS AND EARL R. PEMBROKE, OF SALT LAKE CITY, UTAH.

ORE-ROASTING FURNACE.

1,145,329.

Specification of Letters Patent.

Patented July 6, 1915.

Application filed October 23, 1914. Serial No. 868,225.

To all whom it may concern:

Be it known that we, IRVEN R. MARGETTS and EARL R. PEMBROKE, citizens of the United States, residing at Salt Lake City, in the county of Salt Lake and State of Utah, have invented certain new and useful Improvements in Ore-Roasting Furnaces, of which the following is a specification.

Our invention relates to certain new and useful improvements in machines or apparatus for treating material; it is particularly adapted in the treatment of ores or the like, with a reducing, oxidizing, chloridizing, or sulfatizing roast, and the invention consists of the parts and the constructions, arrangements and combinations of parts, which we will hereinafter describe and claim.

In the accompanying drawings forming part of this specification and in which similar reference characters indicate like parts in the several views;—Figure 1 is a rear elevation of a tray or carrier embodying our invention. Fig. 2 is a side elevation of the same. Fig. 3 is a plan view of the frame or support for the formanious bottom of the tray or car. Fig. 4 is a plan view of the screen bottom support and screen showing part of the latter broken away. Fig. 5 is an elevation of the same partly broken away. Fig. 6 is a plan view of an annular or segmental furnace showing a plurality of trays or carriers movably mounted thereon. Fig. 7 is a vertical sectional view on the line X—X of Fig. 6. Fig. 8 is an enlarged vertical section of one of the trays or carriers showing the dumping bottom and co-acting parts.

The present invention has particular reference to the construction, mounting and operation of the trays or carriers which are each designed to contain a charge of ore or other material to be treated. These trays or cars may be used in connection with any desired type of furnace. For purposes of illustration we have shown them associated with an annular or segmental furnace and wherein the said trays or carriers are mounted to travel about a fixed center or axis, but it will be understood that our invention is not restricted to this type of furnace, and that it comprehends and includes any and all types of furnace, whether circular or otherwise, and where the salient features of the invention may be used to advantage.

When using our invention in connection with an annular or segmental furnace, the

furnace structure may be built of any desired material and as shown in Figs. 6 and 7, said furnace will comprise suitable concentric or other spaced walls, A, forming between them a chamber, a part of which is utilized as a fire-box, B, or combustion chamber, and another part is employed as a hot air chamber, and to this end, said chamber B, will be supplied with a grate structure, C, of any suitable character below which is the customary ash-pit, D.

Mounted to travel over the furnace so that the charge of ore may be successively brought within the range of action and thereby subjected to the roasting heat of the fire in the fire-box, are a series of trays or carriers, E, which trays or carriers are connected by plates, E', of sheet iron or otherwise, which fill the space between adjacent trays, said trays or carriers being designed to follow each other in succession, as we will hereinafter describe, and, in the case of the annular or segmental furnace shown, the trays or carriers, are designed to move about a central axis which is herein shown as in the form of a hollow pipe, F, one end of which is adapted to connect, by any suitable means, with a suction fan, not shown, or other means, for inducing a draft or suction through said pipe; the upper end of the pipe, F, is closed and said pipe has radial branches G, which are each valve-controlled and which radial pipes in turn connect with the interior of the ore tray or carrier by a suitable connection through the inner side thereof, whereby the gases liberated during the roasting or other treatment of the ore may be drawn off through the radial pipes and the central stand pipe and be delivered to a condenser or other suitable medium, not shown.

If a furnace of annular or segmental form is used as in the present illustration, rotation may be imparted to the trays or carriers by any suitable means; for instance, we may adopt a driving mechanism which will include a gear wheel, H, fixed to the central stand pipe or sleeve, I, and engaged and driven by a pinion, J, on a shaft, which carries a band wheel, J', or like device for imparting power to the gear and thereby giving rotation to the series of trays or carriers.

The trays or carriers, E, are each provided with a suitable guide rail or support which is herein shown in the form of an inverted

railroad rail, K, said rails being appropriately secured to the outer sides of the tray or carrier and adapted to be supported upon suitable rollers, L, as shown in Fig. 7.

Referring to Figs. 1 and 2, where the trays or carriers are shown in detail, it will be seen that each of said trays or carriers is provided with a removable lid or cover, M, which forms a closure for the upper side of the tray, thus inclosing the ore chamber formed in the tray and providing for the removal of the gases through the suction pipes, G and F, before mentioned. Each of the trays or carriers is also provided with a perforated or foraminous bottom, N. The arrangement of this bottom may be as desired, but for purposes of illustration we have shown the bottom as of a hinged character; that is, the bottom is hinged along one edge and provided with means along the other edge whereby the bottom may be secured in its normal horizontal position during the roasting or other treatment of the ore, or other material, and said bottom may be permitted to tilt downwardly about its hinged connection to dump the ore, as we will hereinafter explain.

The bottom of each of the trays comprises a support, O, of suitable material and which may be in the form of a grid made either as a solid casting or otherwise constructed to suitably support a screen or foraminous plate, P, upon which the ore is supported during its treatment. The character of this foraminous plate is unimportant except that it shall be sufficiently porous to allow for a circulation of air or gases up or down as the case may be through the ore mixture and bottom of the tray, it being understood that the foramina of the plate or bottom shall be sufficient to hold the ore mixture in place during the travel of the tray from one point to another.

At one side, say the side opposite the hinged connection of the bottom, suitable spring latches, Q, are employed, and which are designed to engage the free side of the bottom to thereby hold the same in a normal locked position during the time that the tray is passing over the fire-box of the furnace, and to the point where the ore is to be discharged. Approximately at this latter point, there is arranged a means for, first, tripping the spring latches, Q, and thereby permitting the bottom of the tray to tilt downwardly and dump a supported charge of ore, and second, other means for restoring the tilting bottom to its normal position after unloading and during the travel of the tray or carrier to the point where a fresh charge is placed therein.

In Fig. 8, we have disclosed an enlarged cross section of one of the trays or carriers, E, in its dumping position, the spring latches having been first engaged by a stationary

stop or lug, R, which is interposed in the path of a crank arm, S, or like part fixed to the latches in such manner that as the crank arm engages the lug during the travel of the tray or carrier, the arm is moved thereby rocking the spring latches and releasing the free edge of the hinged bottom of the tray or carrier and permitting said bottom to tilt downwardly and thereby discharge the supported load of ore. In the path of travel of the tray or carrier is also arranged suitable means for again closing the door after the dumping operation. In Fig. 8 this door-closing means is shown in the form of a stationary iron, T, with which the hinged bottom of the tray or carrier engages and by which this bottom is elevated and caused to be again engaged by the spring latches, S, by the aforesaid bottom riding over and engaging the stationary iron, T, which is preferably inclined to facilitate this closing movement.

In operation a charge, say of ore ground to the necessary degree of fineness, mixed with salt NaCl, and if necessary, according to the conditions, some powdered coal or charcoal, and all slightly moistened, is put into a tray or carrier and moved slowly over the firebox and hot air chamber of the furnace to the desired dumping point, it being understood that the spaces between the trays is filled by the plates, E', in order that there shall be no open spaces passing over the fire-box.

When using a series of trays in connection with an annular furnace, of the type substantially as shown in Figs. 6 and 7, the series of trays may be revolved slowly and continuously or they may be revolved intermittently the width of a tray at one time. The tray with its charge of ore or other material is caused to pass over the fire in the fire-box and to be subjected to the action of the same for any required length of time.

As the interior of the tray or carrier connects with a suction apparatus, and the tray or carrier is closed on all sides, it is apparent that the gases and products of combustion which accumulate in the tray above the charge of ore, will be drawn off through the radial pipes, G and central stand pipe, F, a suction being maintained if desired, for the purpose of creating a draft and circulation through the charge of ore.

As the first of the trays passes the fire-box, the next tray of the series will pass over the box and have its charge of ore subjected to the roasting action thereof, and as the preceding tray passes on the oxidizing or chloridizing, &c., roast once well started progresses to a point, say for a particular ore, where the damper in the individual suction pipe, G, of that particular tray can be regulated by some suitable arrangement, as by an engaging lug, to more or less close the

damper and thereby control the passage through the suction pipe of that particular tray or carrier, or to completely cut off said passage, if desired. The tray passes onward to the point of dumping, which may be 5 say two divisions back of the fire-box. At this point the suitably arranged and permanently fixed lug, R, is located and which is designed to engage with the short lever arm, or crank, S, which is fixed to the spring catches, Q, and as this lever arm passes said fixed lug, it is raised thereby, thus opening the catches against the tension of their closing springs, Q', and tripping the hinged bottom of the tray to allow the supported ore to be discharged. In passing over the lug, R, the catches assume normal position. As the tray is moved one more tray division, 10 the open bottom engages the stationary or permanently fixed iron, T, or like part and as it rides over the same the door is closed, but just before reaching its closed position, a second lug, U, engages the lever arm, S, and rocks the same so as to retract the spring catches to thereby allow the door to close 15 into its full normal position, after which the lever arm rides past the lug, U, when the springs cause the catches to assume their normal position below and secure the free 20 edge of said bottom. At this point, the tray has reached the reloading station, and the tray ahead is being heated initially. The next movement opens, by some suitable lug arrangement, the damper in the suction pipe 25 to the tray just loaded and the operation continues similarly and continuously for all 30 trays consecutively. All gases may be taken through the suction pipe and if the process requires it the gases are discharged into a 35 condensing tower, not shown.

40 From the foregoing, it will be understood that the material is treated in a continuous operation in unit charges or batches by a series of trays or carriers; that these trays or carriers may be of any desired number 45 and may have any desired movement, circular or otherwise, and that they are so arranged that they have movement relative to a fire-box whereby the ore charge is subjected to the action of the heat and products 50 of combustion in the fire-box. It will also be apparent that the trays or carriers are automatically dumped consecutively and that the dumping bottoms are automatically, 55 or otherwise, restored to their normal closed position after dumping.

60 It will also be apparent that the circulation through individual trays can be regulated and controlled.

65 Having thus described our invention what we claim as new and desire to secure by Letters Patent is:—

1. The combination with a furnace having a fire-box, of a horizontally traveling carrier unit designed to receive a charge of

material to be treated, said unit having a foraminous bottom, and means for moving the unit over the fire-box.

2. The combination with a furnace having a fire-box, of a series of transversely connected horizontally traveling carrier units each designed to receive an individual charge of material to be treated each of said units being covered on top and having a foraminous bottom, and means whereby 70 said units are caused to successively pass over the fire-box.

3. The combination with a furnace having a fire-box, of a series of traveling carriers each adapted to receive an individual 80 charge of material to be treated, each of said carriers having a bottom adapted to admit furnace gases to the interior of the carrier as said carrier passes over the fire-box, and means whereby said carriers are caused to 85 successively pass over said fire-box.

4. The combination with a furnace having a fire-box, of a series of horizontally traveling carriers each adapted to receive an individual charge of material to be treated, 90 and means whereby said carriers are caused to successively pass over said fire-box, each of said carriers having a cover.

5. The combination with a furnace having a fire-box, of a series of traveling carriers each adapted to receive an individual 95 charge of material to be treated, and means whereby said carriers are caused to successively pass over said fire-box, each of said carriers having a dumping bottom.

6. The combination with a furnace having a fire-box, of a series of traveling carriers each adapted to receive an individual charge of material to be treated, means whereby said carriers are caused to successively pass over said fire-box, each of said carriers having a hinged bottom upon which the material is supported, and releasable latching means engaging said bottom to hold 105 the same in normal closed position.

7. The combination with a furnace having a fire-box open at the top, of a series of traveling carriers each adapted to receive an individual charge of material to be treated, said carriers adapted to successively pass over said fire-box, and having foraminous bottoms upon which the material is 110 sustained.

8. The combination with a furnace having a fire-box open at the top, of a series of traveling carriers each adapted to receive an individual charge of material to be treated, said carriers adapted to successively pass over said fire-box, and having foraminous bottoms upon which the material is 115 sustained, said bottoms being hingedly secured at one side, and latching devices at the other side of the bottoms for detachably securing the same.

9. The combination with a furnace hav-

ing a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, and means disposed in the range of travel of the carriers for tripping said latching devices.

10. The combination with a furnace having a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, and means for tripping said latching devices to allow the bottoms to dump the treated charge.

11. The combination with a furnace having a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, and means disposed in the path of movement of the carriers for automatically tripping said latching devices.

12. The combination with a furnace having a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, means disposed in the path of movement of the carriers for automatically tripping said latching devices, and means for restoring the bottoms to normal closed position after dumping.

13. The combination with a furnace having a fire-box open at the top, of a series of traveling carriers each adapted to receive

an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, means disposed in the path of movement of the carriers for automatically tripping said latching devices, and stationary means in the path of travel of the carriers for automatically restoring the bottoms to normal closed position.

14. The combination with a furnace having a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, latching devices at the other side of the bottoms for detachably securing the same, means disposed in the path of movement of the carriers for automatically tripping said latching devices, and means for automatically resetting the hinged bottoms.

15. The combination with a furnace having a fire-box open at the top, of a series of traveling carriers each adapted to receive an individual charge of material to be treated, said carriers adapted to successively pass over said fire-box, and having foraminous bottoms upon which the material is sustained, said bottoms being hingedly secured at one side, and releasable connections between said bottoms and the carriers permitting the bottoms to dump the supported charge.

16. The combination with a furnace having a fire-box, of a series of closed carrier units each designed to receive an individual charge of material to be treated, and means whereby said units are caused to successively pass over the fire-box, each of said carriers having a foraminous bottom, and a suction pipe connecting with the interior of the carriers and through which gases are caused to pass.

In testimony whereof we affix our signatures in presence of two witnesses.
